UNITED STATES PATENT OFFICE.

GRACE Q. ARMSTRONG, OF NEW YORK, N. Y.

DESIGN FOR A DOLL.

Application filed April 1, 1929. Serial No. 30,692. Term of patent 3½ years.

To all whom it may concern:

Be it known that I, GRACE Q. ARMSTRONG, a citizen of the United States, residing at New York, in the county of New York and State of New York, have invented a new, original, and ornamental Design for Dolls, of which the following is a specification, reference being had to the accompanying drawing, forming part thereof.

In the drawing:

Fig. 1 is a front view of the doll, and
Fig. 2 is a side view of the doll.

I claim:

The ornamental design for a doll as shown.

GRACE Q. ARMSTRONG.
